UNITED STATES PATENT OFFICE

GEORGE E. WARREN, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY

SHOE MACHINE

Application filed January 30, 1924, Serial No. 689,562, and in Great Britain February 1, 1923.

My invention relates to machines for use in the manufacture of shoes. More particularly, it concerns such fastening-inserting apparatus as that employed for the attachment of heels by nailing.

So far as I am aware, machines used heretofore for securing heels to shoes have comprised distinct devices, as a jack and a heel-clamp, for holding the shoe and heel for the attaching operation. To each of these devices, the work-portions are separately applied, commonly in a receiving position, from which they are moved into attaching relation, or that in which the heel-seat of a shoe and corresponding end of a heel are alined, and then brought together, under pressure, for the driving of the attaching nails or other fastenings. In such an apparatus, there is opportunity for wide variation in the positions which the shoe-portions may assume, considered both longitudinally and transversely of the shoe, and also angularly about the vertical axis of the heel. The correctness of location of the portions is dependent upon the care of the heelng machine operator and his assistant and the manner in which the apparatus is constructed and maintained in condition. Even under favorable circumstances, there is opportunity for considerable departure from the desired relation, and it is necessary to compensate for such errors by bringing the heel to its final form, as by trimming and breasting, after it is in place upon the shoe. This is open to objection, in that these operations add materially to the expense, since they require considerable skill, and in performing them the work may be injured.

Accordingly, an object of the present invention is to provide a machine such as, in its more essential particulars, is disclosed in an application in my name bearing the Serial Number 252,628 and filed in the United States Patent Office September 4, 1918, and in the continuing application, Serial Number 476,659, filed June 11, 1921, patented Mar. 26, 1929, #1,706,504, and of which, as to common subject-matter, the present case is a continuation, by which machine such operations upon a shoe as those

above indicated may be performed with accuracy and ease, and which will permit the attachment of a heel in its final form, so that it requires thereafter neither trimming nor breasting. In the attainment of this object, I utilize a work-support, as the jack of a heel-attaching machine which carries the shoe while it is being operated upon, said support having means arranged to hold a heel in predetermined position for the operation. For thus positioning the heel, the support preferably has a surface, furnished by a projection, which may be termed a jig-pin, arranged to contact with a corresponding positioning surface upon the heel, this latter surface being shown as the wall of an opening or jig-hole within said heel. By so arranging the projection that it will pass through the heel-seat of the shoe and enter the heel, the relation between these elements is fixed with precision, both longitudinally and transversely of the shoe, and there may be predetermination of the relation between such shoe, its heel and the operating mechanism. This is without the exercise of special care and with minimum effort by the operator, and undisturbed by the manner in which the machine is assembled and adjusted. By having a plurality of projections or positioning members to engage the work, the angular relation between the heel, heel-seat and operating mechanism may also be determined. Since I prefer to operate upon the heel from within the shoe, I may employ operating devices movable in the support, there being illustrated passages in said support opening adjacent to the positioning means, in which passages act reciprocatory nail-drivers. This arrangement more definitely locates the points of insertion of the fastenings than when the inserting mechanism is independent of the work-support.

In the accompanying drawing is shown one of the many embodiments which my invention may assume,

Fig. 1 being a front elevation of a heel-attaching machine organized in accordance with this invention;

Fig. 2, an enlarged perspective view of the

fastening-inserting mechanism and work-positioning means; and

5 Fig. 3, a vertical, longitudinal, sectional detail through the die-block, with a portion of a shoe and a heel in place upon it.

The general structure of the illustrated machine may be conveniently that of the well-known lightning heeler, which is the subject of United States Patent No. 446,885, 10 Pope, February 24, 1891. This includes a frame 10, in which side rods 12, 12 are mounted to reciprocate vertically under the influence of a cross-head 13 movable at the bottom of the frame by eccentric mechanism 15 14 driven from a power-shaft 16. Mounted to slide vertically in the frame is a cross-head 18, movable by oscillatory cams 20 and 22 actuated by connections 24 to the side rods. Carried in vertical ways upon the 20 cross-head is a slide 26, joined to said cross-head 18 by a screw 28. A rack and pinion 30, united at 32 to a treadle 34, permits the slide to be raised and lowered independently of the cross-head to apply preliminary pressure to the work. Movable in horizontal 25 ways upon the top of the slide 26 is a work-support or jack 36, its travel manually in the ways allowing it to occupy either a position drawn forward to facilitate the application of the work, or rearward beneath an abutment 37 for the attaching operation. The abutment extends horizontally across the top of the frame, in vertical alinement with the slide 26. The jack 36 has, rising 30 from its upper portion, a post 38 terminating in a horizontal plate 40. Spaced from the plate is a die-block 42 carried upon the upper extremity of vertical rods 44 fixed to the plate and so spaced from each other as to give the die-block proper support. The 35 periphery of the block 42 is of such size and shape that the heel-portion of a shoe-upper may readily be placed over it, while its upper surface 46 generally conforms to the insole-surface at the heel-seat. Formed vertically through the die-block are nail-receiving passages 48, these being arranged in accordance with the particular nailing design which is to be employed for the attachment 40 of the heels.

45 Guided to reciprocate axially in the post 38 is a stem 49, having at its end, between the plate 40 and the block 42, a driver-plate 50, which is guided by the rods 44 passing through openings in it. Mounted at their lower ends in the plate 50 are fastening-inserting devices, shown as in the form of drivers 52, these having their upper extremities operating in the passages 48. The bottom 55 of the stem 49 lies in close proximity to and is alined with a plunger 54 arranged for vertical movement in the slide 26. This plunger is supported upon a bell-crank-lever 56 fulcrumed upon the slide and joined by a 60 link 58 to a bell-crank-lever 60, which may

turn about the axis of the cam member 22. A link 62 unites the lever 60 to the cross-head 13. The connections between the side rods 12 and the cam mechanism 20, 22 and between the cross-head 13 and plunger 54 are such that in the operation of the machine, the cross-head 18 is first elevated, to move the jack toward the abutment 37 and subject the supported work to pressure, and then the drivers raised to insert the fastenings.

The surface 46 of the die-block carries work-positioning means, this preferably taking the form of jig-pins or projections 64, of which two are illustrated. These pins may be located at separated points along the longitudinal axis of the die-block, and are shown as of sufficient height to pass through similarly spaced openings *s* in the heel-seat-portion of a supported shoe *S* and into registering jig-holes or openings *h* in a heel *H* which is to be attached. This heel may be in its final form, save for such superficial operations as burnishing. The diameter of the openings and their location in the shoe and heel are such that when the work is assembled upon the jack in the manner just outlined and particularly illustrated in Fig. 3 of the drawing, the insertion of nails *N*, held in the passages 48 on the drivers 52, will attach the heel in the correct, predetermined location desired in the finished shoe and with the nails in a definite relation to the periphery of the heel. This result is attained because, having formed the surfaces within the openings *s* and *h* and located the corresponding guiding surfaces of the pins 64 and those of the die-block-openings 48 in a predetermined relation, standard conditions will have been established, which will govern every operation performed, without calling for the exercise of judgment or skill on the part of the operator.

In heeling a shoe by my improved apparatus, the operator, with the jack 36 drawn out, loads the die-block-passages 48 with nails *N*, places the upper of a shoe *S* above the die-block 42, bringing the openings *s*, which have been previously formed in the heel-seat-portion of the insole, over the pins 64, and then applies a heel *H* with its openings *h* upon said pins. The shoe-portions are now definitely located with respect to each other and to the die-block-openings, both longitudinally and transversely of the shoe and angularly, considering a vertical axis through the heel-seat. The jack is then thrust in, so that it is beneath the abutment 37, and its stem 39 alined with the plunger 54. Preliminary pressure is thereupon put upon the work by screw 28, actuated by the treadle 34, and the machine started in operation by raising a lever 66, controlling the clutch mechanism, which is not illustrated. Power is thus applied to operate the cam mechanism 20 and 22, raising the jack under power to more

firmly press the tread-surface of the heel against the abutment and upon the heel-seat of the shoe, and the drivers rise, forcing the nails N through the insole into the heel, thus completing the attachment. When, at the end of the cycle, the jack is restored to its normal lowered position, it may be drawn out and the heeled shoe removed. The openings s in the insole may be concealed in any convenient manner. While my invention has been described in connection with a heel-attaching machine, where it is of especial utility, it is to be understood that it may be employed wherever it is desired to locate a heel upon a support for an operation upon it.

Having described my invention, what I claim as new and desire to secure by Letters Patent of the United States is:

1. In a machine for inserting fastenings in a heel provided with positioning surfaces, a work-support provided with complementary positioning members constructed and arranged respectively to engage said positioning surface or surfaces, and mechanism for inserting fastenings in the heel, said mechanism and the support being maintained in a predetermined relation to each other.

2. In a heel-attaching machine, nail-driving mechanism, and a shoe-support having means arranged directly to engage and hold a heel in a predetermined relation to the driving mechanism.

3. In a machine for attaching a heel provided with a hole, nail-driving mechanism, a shoe-support, and a member carried by the shoe-support and arranged to enter the hole in the heel and position said heel to receive nails driven by said mechanism to attach the heel to a supported shoe.

4. In a machine for attaching heels to shoes, the combination with mechanism constructed and arranged to drive nails to effect such attachment of the heels, of a shoe-support provided with means constructed and arranged to engage a heel directly and maintain it in predetermined relation to the nail-driving mechanism during the heel-attaching operation.

5. In a machine for inserting fastenings, a shoe-support having fastening-receiving passages and heel-engaging jig-pins, and fastening-drivers operating in the passages.

6. In a shoe machine, mechanism for operating upon a shoe, and a support arranged to enter a shoe and provided with a surface arranged for contact with a corresponding surface upon a heel during the operation of the mechanism.

7. In a shoe machine, means for operating upon a shoe and its heel, and a support for the shoe during the operation, said support having means constructed and arranged to engage separately a shoe and a heel and to maintain them during the operation in pre-

determined relation to each other and to the operating means.

8. In a heel-attaching machine, mechanism for inserting fastenings for the attachment of a heel, and a support for a shoe during the attaching operation, there being separated pins projecting from the support, said pins being arranged to enter holes in both the shoe and heel and hold them in predetermined relation to each other and to the fastening-inserting mechanism.

9. In a shoe machine, a shoe-support, devices movable upon the support for operating upon a supported shoe, and heel-positioning means carried by the support.

10. In a heel-attaching machine, reciprocating drivers, and a jack for supporting a shoe to receive the action of the drivers, said jack being provided with a projection arranged to pass through the heel-seat of the jacked shoe and to enter a heel to position the heel and shoe for the attaching operation.

11. A machine of the class described having, in combination, a work-support having projections provided with positioning surfaces arranged to co-operate with corresponding surfaces within openings formed in unattached heels to control the position thereof during the performance of an operation thereon, and means for operating upon the heels while thus positioned.

12. A machine of the class described having, in combination, means for inserting fastenings in heels, a work-support arranged to present heels to the fastening-inserting means, a plate carried by the work-support and arranged to receive heels, said plate having positioning surfaces arranged to co-operate with corresponding positioning surfaces formed upon the heels to control the presentation of the heels to the fastening-inserting means, and a co-operating plate arranged to apply pressure to heels thus positioned.

13. A machine of the class described having, in combination, heel-positioning means provided with jig-pins arranged to enter corresponding jig-holes formed in unattached heels to control the position thereof, and means for operating upon the heels while their position is thus controlled.

14. A machine of the class described, in combination, means for operating upon heels, and a heel-support provided with a jig-pin arranged to enter corresponding jig-holes in the heels to control the position of the heels during the operation thereon.

In testimony whereof I have signed my name to this specification.

GEORGE E. WARREN.
